UNITED STATES PATENT OFFICE.

FREDERIC T. DANA, OF WISCASSET, MAINE.

DESIGN FOR A CLOTHES-LINE BLOCK.

SPECIFICATION forming part of Design No. 16,339, dated October 20, 1895.

Application filed August 26, 1895. Serial No. 175,399. Term of patent 7 years.

To all whom it may concern:

Be it known that I, FREDERIC T. DANA, a citizen of the United States, residing at Wiscasset, in the county of Lincoln and State of Maine, have invented and produced a new and original Design for a Clothes-Line Block, of which the following is a specification.

My design for a clothes-line block consists in a peculiar hook-shaped configuration of the block, substantially as hereinafter described, and shown in the accompanying drawing.

Reference is to be had to the accompanying drawing, which forms a part of this specification, and which represents a view in perspective of a clothes-line block embodying my design.

The block A is of hook shape, having a marginal configuration when viewed from its side, which is made up of a series of curved and straight lines, as follows: The eye or butt end of the hook-shaped block is of circular form, as at b, joining the outline of the back of the block, which is of a straight-line configuration, as at c, extending up to the front outline of the nose end of the hook-shaped

block, which outline is also of a straight-line configuration at right angles to that of the back, as at d, and joins a face straight outline, e, parallel with the outline c of the back. From this point, at the inner termination of 30 the outline d, which presents a rounded form for the nose end s of the hook-shaped block, the configuration of the remaining portion of the side outline presents a straight line, f, running toward the front end of the block, 35 with an inclination toward the back outline, e, and joining a concave outline, g, which is continued by a gentle curve, h, to the circular outline b of the butt or eye end of the block.

I claim—

The design for a clothes-line block, consisting of a series of curved and straight lines composing the marginal configuration of the side of the block, as herein shown and described.

FREDERIC T. DANA.
